UNITED STATES PATENT OFFICE.

ARTHUR E. FRANCIS, OF CLEVELAND, OHIO, ASSIGNOR, BY MESNE ASSIGNMENTS, TO
THE CASKEY-DUPREE COMPANY, OF MARIETTA, OHIO.

ELECTRIC MULTIPLE SWITCH.

1,306,885.

Specification of Letters Patent. Patented June 17, 1919.

Application filed October 10, 1917, Serial No. 195,693. Renewed April 28, 1919. Serial No. 293,374.

To all whom it may concern:

Be it known that I, ARTHUR E. FRANCIS, a citizen of the United States, residing at Cleveland, in the county of Cuyahoga and 5 State of Ohio, have invented certain new and useful Improvements in Electric Multiple Switches, of which the following is a specification.

This invention relates to electric switches, 10 and has for its object to provide an improved multiple switch for controlling two circuits, such as the horn circuit and the light circuit of an automobile. The structure of the device is such that it can be conveniently mounted 15 upon the steering post of an automobile, in position for operation by either hand of the driver, or upon the spark or similar controlling lever in some type of machines.

The device embodies a switch of the push 20 button type which can be used for the horn circuit, and another switch of the rotary type which can be used for the lighting circuit or for a dimmer in said circuit, the push button being pressed to control one circuit 25 or turned to control the other, and one operation does not interfere with the other. A multiple control is therefore provided by the manipulation of a single member.

The invention is illustrated in the accompanying drawings, in which—

Figure 1 is a vertical section of the device, shown applied to the steering post of an automobile.

Fig. 2 is a section on the line 2—2 of Fig. 35 1, with a diagram of the horn circuit.

Fig. 3 is a section on the line 3—3 of Fig. 1, with a diagram of the lighting circuit.

Fig. 4 is a section on the line 4—4 of Fig. 1.

40 Figs. 5 and 6 are sectional views of a modification.

Referring specifically to the drawings, 1 indicates a nut which secures the steering 45 wheel A to the steering post B, 2 indicates a shell or casing, the lower end 3 of which is hexagonal to fit closely on the nut 1, where it is held by screws 4 tapped into the sides of the nut. A block 5 of insulating material is fitted within the shell or casing, and has a 50 depending flange 6 at the bottom which rests on top of the nut, forming a space under the block. The block also has an upstanding flange 7 at the top which is confined by an inturned flange 8 at the rim of 55 the casing. A push button 9 fits within the

top of the casing and has a pin 10 projecting downwardly through a hole in the insulating block 5. This pin has a groove 11 near its lower end, which is engaged by a fork on one end of a spring contact piece 12. 60 The other end of the contact piece 12, is fastened to the block 5 by a screw 13. One end of the horn circuit 16 is also connected to the screw 13. Below the member 12 is a contact piece 14 connected to the block 5 and 65 to the other side of the circuit by a screw 15. By pushing down on the button 9 the pin 10 closes the contacts 12 and 14 and sounds the horn. The spring 12 normally acts to lift the push button. 70

Between the upper face of the block 5 and the lower face of the button is a circular disk 18 which has upwardly projecting lugs 19 at opposite points, and these lugs 19 fit in grooves 20 in the lower face of the 75 button. The piece 18 is also provided at its periphery with segmental spring fingers 21 having bosses 22 at the ends thereof adapted to engage with contact pieces 23, 24, 25, and 26 in the lighting circuit, or to engage in depressions 27, and 28 in the block 5 when the lighting circuit is opened. The contact depressions 25 and 26 are formed in a metal piece 29 set in the face of the block 5 and connected to one side 30 of the circuit 80 of the lamps 41. The contact piece 24 is connected to the other side 35 of the circuit, which may also be provided with a cross connection 36 having a switch 40 therein. The contact piece 23 is connected to a shunt 85 circuit 32 having therein a resistance 33. The various wires may be entered into the casing through an opening 45 and attached to the respective contacts by the screws 31, 34 and 37. 90

The lighting circuit is controlled by turning the button 9, causing the arms 21 and 22 carried thereby, to connect the respective terminals. When the terminals 24 and 26 are connected, the lights are full on. When 100 the points 23 and 25 are connected, the resistance 33 is in circuit, thus dimming the lights. In off position the bosses 22 rest in the notches 27 and 28. The block 5 has a projecting pin 38 which works in a segmental groove 39 of the button, and so limits the turn thereof. 105

It will be seen that by pushing in the button, the horn circuit is closed, and by turning the button, the lighting circuit is con- 110

trolled. This provides for very convenient operation of the respective circuits, and the device has the further advantage that it may be cheaply constructed and readily applied to the steering post.

In the modification shown in Figs. 5 and 6 the switch casing 2^a is applied to the hub 52 of the lever 51 mounted on the "spark tube" 50 and held by a spring 53 engaging 10 in a groove 54 in the casing and a groove 55 in the hub. The circuit shown in Fig. 6 includes the side lights 56 in the circuit 57 substituted for the circuit 32 and coil 33 above described.

15 I claim:

1. In a selective switch, the combination of a casing, an insulating block inclosed therein and having separate sets of contacts secured to its opposite faces respectively, 20 and a push button slidable and rotatable in one end of the casing and having a pivot pin slidable axially in the block, the push button being provided with means to close the set of said contacts on one side of the block by turning movement, and the pivot pin coöperating with the set of contacts on the opposite side of the block to close the same when pushed in.

2. In a selective switch, the combination 25 of a tubular casing, an insulating block inclosed in the casing, a pivot pin extending

through the block and slidable axially therein, a set of contacts mounted at the inner end of the block in axial alinement with the pin and adapted to be closed when the pin 35 is pushed in, a push button rotatably mounted in the casing on the outer end of said pivot pin, and another set of contacts located between the push button and the outer end of the block and adapted to be closed by 40 turning the push button.

3. In a selective switch, the combination 45 of a tubular shell, an insulating block extending across within the same and having a central hole therethrough, a pair of contacts attached to the inner end of said block, one of said contacts comprising a spring, a central pivot pin slidable in and out in said hole and engaging said spring, a push button mounted upon the outer end of said pin 50 and adapted when pressed in to advance the pin in opposition to the spring and close said contacts, and another set of contacts located between the push button and the outer end of the block, in position to be 55 closed by turning the push button.

In testimony whereof, I do affix my signature in presence of two witnesses.

ARTHUR E. FRANCIS.
